UNITED STATES PATENT OFFICE.

WILLIAM HOWARD COLE, OF NEW YORK, N. Y., ASSIGNOR TO ELOC COMPANY, OF NEW YORK, N. Y.

APPARATUS FOR UNITING METALS.

No. 878,869.

Specification of Letters Patent.

Patented Feb. 11, 1908.

Original application filed December 6, 1904, Serial No. 235,707. Divided and this application filed May 6, 1905. Serial No. 259,101.

To all whom it may concern:

Be it known that I, WILLIAM HOWARD COLE, a citizen of the United States, and a resident of the borough of Brooklyn, city and 5 State of New York, have invented a new and Improved Apparatus for Uniting Metals, of which the following is a full, clear, and exact description.

My invention relates to an improved apparatus for uniting metals, and more particularly for uniting metals of different melting points, and is a division of a prior application filed by me December 6, 1904, Serial No. 235,707.

15 In the accompanying drawings, in which similar reference characters refer to corresponding parts, I have illustrated a preferred form of apparatus which embodies my invention. Evidently, however, this apparatus 20 may be considerably modified without departing from my invention, and may be used to carry out any process whatsoever for which it is suitable.

25 In this application I make no claim for a process, but for the sake of clearness will herein describe one process which can be carried out by the use of this apparatus, and for which the particular form of apparatus illustrated has certain advantages.

30 In these drawings Figure 1 illustrates in vertical cross-section an apparatus of one form which may be used in carrying out my invention for the purpose of welding a copper bond to one flange of a rail section; Fig. 35 2 is a horizontal cross-section partly in plan taken on the line 2—2 of Fig. 1. Fig. 3 is the same view as Fig. 1, showing approximately one form of result which will be produced after my process is completed and before the removal of the apparatus used therewith; Fig. 4 is the same view as Fig. 2, illustrating the same conditions illustrated in Fig. 40 3; Fig. 5 shows the same general type of apparatus applied for the joining of a metal plate and a metal rod; Fig. 6 is a cross-sectional view corresponding to Fig. 1, but illustrating a modification; and Fig. 7 is a cross-section of the insert illustrated in Fig. 6.

45 Referring to these drawings (Figs. 1 to 4), 50 5 designates the web of a rail section, 6 the top or tread of the same, and 7 the flanges thereof.

55 13 designates what may be called a bond which, of course, may be of any form, but which is shown as in the form of a rod. As

shown (Fig. 1) this metal rod 13 has its inner end 13^a resting upon and in direct contact with the upper surface of one of the flanges 7.

8 designates a mold of refractory material having a mold chamber 12. As shown, this mold chamber is provided with a tapering or conical portion 12^a. As shown in Figs. 1 to 5, inclusive, this tapering portion 12^a is secured by making the mold substantially integral throughout, and leaving a mold chamber of such a configuration. On the other hand, the mold may be formed to leave a mold chamber of any desired shape, such as the chamber 12^x, shown in Fig. 6. In this case an insert 12^y may be provided and made 70 removable. When this is done the insert will preferably be of such a form as when placed in the mold chamber to form a tapering portion 12^z therein. The mold will, of course, be provided with suitable orifices permitting the insertion into the mold chamber thereof of the metal pieces to be welded together. Obviously, this may be accomplished 75 in any well known manner. The mold chamber is, furthermore, provided with an opening 9^c connecting with a passage 9^a having an open top for the admission of any suitable fusing agent.

In the specific construction illustrated, I have shown a crucible or crucible chamber 9 arranged in the upper portion of the mold, and above the mold chamber. The crucible may, however, be a separate part. When arranged in the upper portion of the mold, it will preferably be separated from the mold 80 chamber by a plug or disk 9^b, which may be fused or tapped by the heat of the fusing agent, or may be tapped manually.

85 Preferably, a refractory material 9^e, such as ground slag, will be superimposed on the plug 9^b temporarily to prevent any fusing or tapping of the plug due to any reaction in the crucible.

90 A vent 11 will preferably be arranged at or near the small end of the tapering portion of the mold chamber in either construction. Another vent 10 will preferably be arranged leading to the atmosphere from any suitable point of the mold chamber 12. Also another vent 16, as shown in Fig. 6, may be arranged.

95 The operation of my apparatus is as follows: When a fusing agent having sufficient temperature to melt the pieces of metal arranged in the mold chamber is admitted to the said chamber, a large portion of the heat 100

105 110

units thereof will obviously be taken up by those portions of the metals which are in the main portion of the mold chamber or outside the tapering portion thereof. Furthermore, 5 as the area of the tapering portion of the mold chamber decreases the effective heat units of the agent would gradually decrease. For example, in the constructions illustrated in Figs. 1 to 4, inclusive, the heat units of the 10 agent which will be effective on the lower portion of the web and on the flange of the steel rail will very largely exceed those which will be effective upon the copper bond 13, even at the commencement of the tapering portion 12^a of the mold chamber. Furthermore, as 15 the tapering portion 12^a gradually decreases in area towards the outer end of the copper bond the heating effect of the agent will also be decreased.

20 I believe that it is broadly new to provide in a mold chamber any means whatsoever for regulating the effective heat units throughout a portion thereof substantially to correspond with the melting point of a 25 piece of metal placed or arranged therein.

For the sake of clearness, I will now describe one process which may be carried out in this apparatus for the purpose of uniting metals. A mixture of an oxygen containing 30 metal and aluminium is to be placed in the crucible and ignited. This will cause a comparatively violent reaction, which were it not for the refractory material 9^a might immediately melt or tap the closing plug 9^b.

35 The intervention of this refractory material, if properly selected, will prevent the immediate fusing of this plug, which will take sufficient time, first to allow the molten metal resulting from the reaction to sink to 40 the bottom of the crucible, whereas the lighter alumina slag will rise to the top; and, second, will permit of the discharge of at least a large proportion of the gases created by the reaction. So soon as the plug is fused, 45 either by the continuing heat of the reaction and the molten metal, or manually, the heavier molten metal will then flow downwards through the connecting passage and into the mold chamber 12. Obviously, it

50 will first strike upon the flange 7, the lower portion of the web 5 of the rail section and the inner end of the copper bond 13. Thereafter it will gradually extend into the tapering portion 12^a or 12^b of the mold chamber 55 12. This will result in the majority of the heat units being applied to the rail section at the innermost end of the copper bond, and then being gradually decreased through the tapering portion of the mold chamber and

60 along the remaining portion of the copper bond. Obviously, it is desirable to have the connecting passage intermediate the crucible and the mold chamber arranged to empty into the main portion of the latter.

65 In Fig. 5 I have shown a modified arrange-

ment from that shown in the other figures, for the purpose of adapting the mold to join a copper rod 13 to a steel plate 15, instead of to a rail as in the other figures. After the mold chamber has become filled with the 70 molten metal there still remains a portion of the fusing agent in the crucible, as indicated by 14^a in Fig. 3. This residue will be principally slag and the crucible and mold chamber are so proportioned that the latter 75 cannot receive all the fusing agent from the former.

What I claim is:

1. In an apparatus for uniting metals of different melting points, a mold having a 80 mold chamber adapted to receive within it portions of the metals to be united and an inlet for the admission of a fusing agent to the chamber, said mold chamber constructed to permit varying quantities of the fusing 85 agent to surround different portions of the metal whereby the heating effect of the fusing agent is decreased on certain portions of the metal having the lower melting point.

2. In an apparatus for uniting metals of 90 different melting points, a mold provided with a mold chamber to receive within it portions of the metals to be united, said chamber having a tapering portion for receiving the metal having the lower melting point. 95

3. In an apparatus for uniting metals, a mold comprising a crucible, a mold chamber, a passage connecting said crucible and said mold chamber, a plug for temporarily closing said passage, and a refractory material 100 arranged over said plug to temporarily protect the same.

4. In an apparatus for uniting metals of different melting points, a mold provided with a mold chamber to receive within it 105 portions of the metals to be united, said chamber having a tapering portion for receiving the metal having the lower melting point, and a vent leading from the smallest end of said tapering portion. 110

5. In an apparatus for uniting metals, a crucible, a mold chamber comprising a main portion and a tapering portion, a passage connecting said crucible and said mold chamber outside the tapering portion of the 115 latter, and said tapering portion having a vent leading from its smallest end.

6. In an apparatus for uniting metals, a crucible, a mold chamber comprising a main portion and a tapering portion, and a passage connecting said crucible and said mold chamber outside the tapering portion of the 120 latter.

In testimony whereof, I have signed my name to this specification in the presence of 125 two subscribing witnesses.

WILLIAM HOWARD COLE.

Witnesses:
